UNITED STATES PATENT OFFICE.

WILLIAM TAYLOR AND FRANCIS WILLIAM PRESTON, OF LEICESTER, ENGLAND.

APPARATUS FOR PREPARING LENSES AND THE LIKE FOR GRINDING AND POLISHING.

1,358,677.

Specification of Letters Patent.

Patented Nov. 9, 1920.

Original application filed October 17, 1919, Serial No. 331,436. Divided and this application filed February 11, 1920, Serial No. 357,865. Renewed September 23, 1920. Serial No. 412,415.

To all whom it may concern:

Be it known that we, WILLIAM TAYLOR, engineer, and FRANCIS WILLIAM PRESTON, engineer, both of Stoughton Street Works, 5 Leicester, in the county of Leicester, England, have invented certain new and useful Improvements in Apparatus for Preparing Lenses and the like for Grinding and Polishing, of which the following is a specification.

10 This invention relates to improved apparatus for use in mounting lenses and the like in preparation for the grinding and polishing operations, and it has for its principal objects to provide appliances with which such mounting may be accomplished more expeditiously than heretofore, and with less risk of springing and distorting the lenses in the mounting.

20 It is usual, in grinding and polishing lenses, to attach each lens to a holder by means of a material such as pitch intervening between the lens and the holder. A number of lenses are frequently held in this 25 way to one holder, so that their surfaces conform to one general surface and may be ground and polished together. Such a group is termed a "block."

30 The customary practice followed in carrying out the operation is liable to give rise to various defects in the finished lenses, the principal defect being due to the fact that the lenses, (apparently through local shrinkage and expansion of the pitch) become 35 strained in such manner that although, so long as the lenses remain on the holder and up to the completion of the polishing process, their surfaces may have a form which is satisfactory, nevertheless when 40 finally removed from the pitch the lenses, being released from strain, become distorted.

45 Systematic investigation of this subject has shown us that, in order to reduce such distortion, the pitch backing on each lens should be placed symmetrically about the axis of the lens; and the backings on all similar lenses in a block should be uniform in size and shape.

50 We further find that, in the case of some lenses, we can reduce the distortion by forming the pitch backing hollow at the center or heart of the mass of pitch.

The method for mounting lenses and the

like which we have invented and the apparatus for placing the lenses in proper position upon the holder are described and claimed in our application for Letters Patent of the United States, Serial No. 331,436, filed October 17, 1919, of which the present application is a division. The present application is directed particularly to apparatus for use in applying the binder to the lenses.

55 In the accompanying drawings, Figures 1 and 2 illustrate, in side elevation and plan respectively, one form of apparatus for heating the pitch, for delivering it to lenses in molds, for closing the molds, and for coating the surface of each lens with "tacky" 60 previous to the application of the pitch. Fig. 3 is a side elevation, partly in axial section, of one of the molds seen in Figs. 1 and 2 (but drawn to a larger scale) together with the plunger which constitutes 65 the closure for the mold; a bi-convex lens being shown in position in the mold. Fig. 4 is a partly sectional side view of a bi-convex lens with the molded mass of pitch 70 adherent to it. Fig. 5 is a side elevation of 75 a convenient form of "tacky" spray-nozzle.

80 11 (Figs. 1 and 2) is the hollow body or container of a mixing machine, of well known type, which we find suitable for use in heating and conditioning the pitch; the 85 container being provided with a steam jacket 12 supplied with steam through a pipe 13, while 14 is a pipe for draining water of condensation from the jacket. The container 11 has a removable cover 15 provided with a hopper 16 for the introduction of fresh pitch into the container, the hopper being normally closed by a cover 17. A pair of rotary paddles 18, 18 mounted on shafts 19, 19 serve to stir up the pitch with 90 in the container 11; the shafts 19, 19 being geared together and adapted to be continuously driven by suitable means (not shown). A steam-jacketed pipe 20 leads from the interior of the container to the point where 95 at the pitch is to be delivered to the molds, this pipe terminating in an obliquely-chamfered dependent nozzle 21 the passage between which and the pipe itself is controlled by a screw-down valve 22 for regulating the rate of delivery of the pitch.

100 105 The mold A shown in detail in Fig. 3 comprises a base portion 23 surmounted by

a circular ledge 24 presenting at its inner side a seating 25 of a diameter to receive and hold the lens to which the pitch is to be applied, the lens being supported around its 5 margin only, while over the outer side of the ledge 24 is removably fitted an annular inwardly-conical cap 26 which, rising above the upper surface of the lens, forms a coaming adapted both to retain the lens in position 10 within the mold and also to confine the pitch laterally during the molding operation. The plunger B which forms the closure for the mold is adapted to be brought into operative position, after the mold has 15 been filled with pitch, by downward movement in the direction of the common axis of the mold, lens and plunger, and, in the example illustrated, comprises an annular rim 27 adapted to contact with the upper 20 edge 28 of the cap 26 and a central circular projection 29 which, by entering the mass of pitch bounded by the cap, forms in said mass a central depression 30, so that the pitch 31 which adheres to the lens 32 when the latter 25 is removed from the mold, presents in axial section the profile shown in Fig. 4.

In order to facilitate the pitching of a number of lenses in succession, a circular series of molds A are detachably mounted 30 upon a horizontal turntable 33 fitted to revolve about a fixed vertical stud 34 and provided at equal intervals with upright pegs 35 (Fig. 2) adapted to enter holes 36 (Fig. 3) in the base portions 23 of the several molds; the turntable 33 being rotated step-by-step through angular intervals corresponding to those separating the pegs 35. For this purpose, in the example illustrated, the turntable 33 has on its lower side a dependent annular flange 37 in which are 35 formed a series of radial grooves 38 opening out at both the external and internal peripheries of the flange; these grooves, which are spaced apart at angular intervals corresponding to those between the pegs 35, being engaged in succession by a pair of crank pins 39 (carrying antifriction rollers) which project vertically from a disk 40 fast on the upper end of a vertical shaft 41 revolved at a 40 suitable speed by any convenient means (not shown). The shaft 41 may be continuously driven through frictional gearing so as to permit of any convenient means (not shown) being employed for arresting the rotation of the turntable 33 periodically during the intervals when successive molds are 45 being dealt with.

As seen in plan view, Fig. 2, the turntable 33 is to be understood as intended to be revolved contra-clockwise so as to bring successive molds A, first, under a spray-nozzle 42 for delivering "tacky" on to the upper surface of each lens 32 in its mold, secondly, under the pitch-delivery nozzle 21, and 50 thirdly under the plunger B which serves as

a closure for all the molds in succession. The "tacky" may be ejected by any convenient means, for example a pneumatically-operated device such as is commonly employed for spraying paint, varnish or the 55 like.

The plunger B, which is shown in Fig. 1 as detachably fixed on the lower end of a vertical spindle 43 so as to be changeable to suit different molds, is actuated by sliding the spindle 43 through a stationary guide 44 supported on a bracket 45 extending from the fixed stud 34 about which the turntable 33 revolves; the upper end of the spindle 43 being connected by a link 46 to a hand-lever 47 fulcrumed at 48 to the bracket 45. The spindle 43 may be normally retained in the raised position, so as to hold the plunger B clear of the molds A, by means of a coiled spring housed within the guide 44 80 but not shown in the drawing. As the plunger is depressed by means of the lever 47 until arrested by the rim 27 encountering the edge 28 of the mold-cap 26, the surplus pitch escapes over the edge 28. After the 85 pitch has set to the shape given to it by the mold and plunger, the plunger is raised and the lens 32 with its adherent mass of pitch can be removed from the mold. The central depression or cavity 30 formed in the mass 90 of pitch, (see Fig. 4) leaves only an annular rim 50 of pitch by which alone the lens is subsequently attached to the holder for grinding or polishing, the central depression or cavity 30 serving to relieve the lens 32 of 95 the strain which would be imposed upon it by the cooling of a solid mass of pitch interposed between the lens and the holder, owing to the shrinkage of such mass, which takes place last at its center, resulting in the 100 drawing-in of the center of the lens and thus 105 causing distortion.

Although we have described the above apparatus as applied to pitch or the like substances capable of being softened by heat, 110 it will be obvious that much of our invention is equally applicable where substances are employed such as plaster of Paris and other cements sometimes used for mounting lenses, which are liable to shrinkage or expansion during setting in the operation of 115 mounting lenses and the like.

Having now particularly described and ascertained the nature of our said invention and in what manner the same is to be performed, we declare that what we claim is:—

1. Apparatus for applying a binder to lenses or the like, comprising a mold, a support for the lens therein, retaining walls above said support, and means for filling the 125 space within said walls with a fluid binder.

2. Apparatus for applying a binder to lenses or the like, comprising a mold, a support within said mold for the lens, retaining walls above said support, a loose fitting clo- 130

sure for said mold, means for filling said mold with a fluid binder, and means for applying said closure to the mold.

3. Apparatus for applying a binder to lenses or the like, comprising a mold having a support for the lens and having an opening at its top, means for introducing a fluid binder into said mold, and a plunger adapted to enter the hole in said mold and 10 to form a central recess in the binder molded therein.

4. Apparatus for applying a binder to lenses or the like, comprising a movable carrier, a plurality of molds upon said carrier 15 each having a support for a lens and an opening at the top, means for pouring a fluid binder into one of said molds, a reciprocating closure adapted to close the hole in one of said molds, and means for causing 20 a step-by-step movement of said carrier so as to bring each mold first under said pouring means and subsequently in line with said plunger.

5. Apparatus for applying a binder to lenses or the like, comprising a movable carrier, a plurality of molds upon said carrier each having a support for a lens and an 25 opening at the top, means for spraying tacky upon a lens in one of said molds, means for pouring a fluid binder into one of said molds, a reciprocating closure adapted to close the 30 hole in one of said molds, and means for causing a step-by-step movement of said carrier so as to bring each mold first under 35 said spraying means and then under said pouring means and subsequently in line with said plunger.

6. Apparatus for applying a binder to lenses and the like, comprising a base having 40 means for supporting the edge of the lens, and a cap detachably fastened to said base and arranged to hold the lens in position upon said base and to provide a chamber in which the binder may be molded.

45 7. Apparatus for applying a binder to lenses and the like, comprising a base having an annular shelf to support the periphery of the lens, and a cap detachably fastened to said base and having an upwardly 50 tapering conical inner surface adapted to contact with the periphery of the lens and hold it in position upon said shelf and to form a chamber for molding the binder.

55 8. Apparatus for applying a backing to a lens, comprising a base having an annular

seat for the lens, a cap detachably fastened to said base and having an upwardly tapering inner surface adapted to contact with the periphery of the lens and hold it in position upon said seat and having an opening 60 at its top and providing a chamber above the lens for molding the backing, and a loose fitting closure for the opening at the top of said cap piece.

9. Apparatus for applying a binder to lenses or the like comprising a mold having a chamber of predetermined volume for the reception of the binder, and means for positioning a lens in predetermined relation to said chamber.

10. Apparatus for applying a binder to lenses or the like, comprising a mold having an opening, means for introducing a fluid binder into said mold through said opening, a closure for said mold adapted to 75 be moved into predetermined relation to said mold so as to force from the mold any surplus binder, and means for positioning a lens in predetermined relation to said mold.

11. Apparatus for applying a binder to lenses or the like, comprising a mold having an opening, means for filling said mold with a fluid binder through said opening, a closure adapted to be brought into contact with the mold at the periphery of said opening so as to force from the mold any surplus binding material and to sever the surplus from the material remaining in the mold, and means for positioning a lens in predetermined relation to said mold.

12. Apparatus for applying a binder to lenses or the like comprising a mold having a chamber of predetermined volume for the reception of the binder, and means for positioning a lens in predetermined relation 95 to said chamber by engagement with the periphery and one face of the lens.

13. Apparatus for applying a binder to lenses and the like comprising a mold, an annular seat in said mold adapted to support the lens by engagement with the outer portion of one side thereof, retaining walls above said seat, and means for filling the space within said walls with a fluid binder.
